ALLEN S. JACKSON, OF KOKOMO, INDIANA, ASSIGNOR TO HIMSELF AND
JOHN F. MYERS, OF SAME PLACE.

Letters Patent No. 76,767, dated April 14, 1868.

IMPROVEMENT IN LANTERNS.

The Schedule referred to in these Letters Patent and making part of the same.

TO ALL WHOM IT MAY CONCERN:

Be it known that I, ALLEN S. JACKSON, of Kokomo, in the county of Howard, and State of Indiana, have invented a new and useful Improvement in Lanterns and Lamps; and I do hereby declare that the following is a full, clear, and exact description of the same, reference being had to the annexed drawings, making part of this specification, in which—

Figure 1 is a perspective view, and

Figure 2 is a vertical section.

The same letters are employed in both figures in the designation of the same parts.

My invention relates to an improvement in lamps, by means of which the flame is protected from the effect of currents of air, and which is therefore peculiarly adapted to use in lanterns; and it consists in the arrangement of plates for diverting the air-currents, and introducing the air in constant quantities to the flame; also in the mode of attaching the chimney, and to the mode of suspending the lamp from the guard-wires of the lantern.

This lamp is designed for burning coal-oil, but other illuminating-fluids may be used. The oil is intended to be put into the body of the lamp A, which is made flat on the bottom, so that it may be used as an ordinary house-lamp. The lamp-burner B is screwed into the base. C is the wick-tube, and D is the wick-regulator. E is a deflector, with a slot corresponding to the form of the flame, attached to standards in such manner that its height may be regulated as required.

A flange-plate, B', is carried upward, as shown in fig. 2, to support the perforated annular plate F, which is perforated with small holes, as shown. An annular deflecting-plate, G, is attached to the plate F at the inner edge by a vertical ring, G'. This plate G does not extend outwards to the flange B', but a narrow opening is left around its entire periphery between the two, so that the current of air, entering through the apertures in plate F, striking against the plate G, shall be deflected outwards, and, passing through the opening between it and plate B', shall pass inwards through the space between them to the flame, both below and above the deflector E. By this means sudden blasts are so interrupted that the air will be supplied in a constant quantity to the flame.

The wire guards of the lantern are shown at H. The lower ends of all these guards are fastened to a wire ring (except two, shown at H') at the bottom, and all of them to a central ring. The wires H' H' are extended under the lower wire, and bent, as shown. The hooks are inserted through slots at F' in the plate F, and, passing out through apertures in the flange-plate B', serve to attach the lamp to the frame of the lantern. I is the top of the lantern, through which the unconsumed products of combustion may escape, and K is the bail.

The chimney L is fitted neatly into the circular opening in the plates F and G within the vertical ring G'. The base of the chimney may be surrounded by a collar. The top of the chimney fits into the lower concave surface of the top, I, which, while it supports the top of the chimney when the lamp is used with a lantern, may be removed when the lamp is used separately, the chimney then being supported only by its base.

What I claim as my invention, and desire to secure by Letters Patent, is—

1. In combination with the base and burner of the lamp, the flange-plate B', perforated annular plate F, and annular plate G attached thereto at G', arranged to operate substantially as and for the purpose set forth.
2. A lantern combining in its construction the following elements: A base and lamp, a flange-plate, B', perforated annular plate F, deflecting annular plate G, ring G', chimney L, detachable frame H H', and top, I, said parts being respectively constructed and arranged in relation to each other substantially as described.

In testimony whereof, I have signed my name to this specification in the presence of two subscribing witnesses.

ALLEN S. JACKSON.
